UNITED STATES PATENT OFFICE.

BENNO VOM EIGEN, OF NEWARK, NEW JERSEY, ASSIGNOR TO AUGUST GOERTZ & CO., A CORPORATION OF NEW JERSEY.

BAG-FRAME FASTENER.

1,139,826.

Specification of Letters Patent. Patented May 18, 1915.

Application filed August 19, 1914. Serial No. 857,452.

To all whom it may concern:

Be it known that I, BENNO VOM EIGEN, citizen of the United States, residing at Newark, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bag-frame fasteners; and, the present invention has reference, more particularly, to a novel fastener for the frames of bags of the various kinds, and made in the form of a spring-controlled catch or lock for the usual hinged frame-sections of bag-frames.

The present invention has for its principal object to provide a neat and simply constructed bag-frame fastener of the general character hereinafter more fully set forth, and which is readily manipulated.

The invention has for its further object to provide a pivotally-disposed knob or finger-piece, arranged upon the upper portion of the shell or box of the fastener, and a novel construction and arrangement of curved spring within the shell or box and coöperating with the knob or fingerpiece to limit its outward and rearward movement when manipulated, and also to return the said knob or fingerpiece to its normal initial position after manipulation.

The invention has for its further object to provide the spring-controlled knob or fingerpiece with a stud, projection, or the like, which projects rearwardly into a slot or opening in the back of the shell or box, and coöperates with the shell or box to prevent the knob or fingerpiece to be inadvertently moved in a forward or downward direction from its normal initial position with relation to the upper surface of the shell or box, but still does not interfere with the outward or inward movement when manipulated, nor with the return movement of the knob or fingerpiece after manipulation.

Other objects of this invention not at this time more particularly enumerated will be

clearly understood from the following detailed description of the present invention.

With the various objects of the present invention in view, the said invention consists, primarily, in the novel bag-frame fastener hereinafter set forth; and, the invention consists, furthermore, in the novel arrangements and combinations of the various devices and parts, as well as in the details of the construction of the said parts, all of which will be more fully described in the following specification, and then finally embodied in the clauses of the claim which is appended to the said specification and forms an essential part of the same.

The invention is clearly illustrated in the accompanying drawings, in which:

Figure 1 is a fragmentary view, in front elevation, of the frame-sections of a bag-frame in their closed relation, with a bag-frame fastener made according to the principles of the present invention, the bag-frame fastener being also shown in front elevation. Fig. 2 is a top or plan view of the parts represented in said Fig. 1, the portions of the frame-sections, and the bag-frame fastener and its hasp-plate, however, being represented in their separated relation. Fig. 3 is a front face-view of the fastener, with the hasp-plate omitted from said view, and Fig. 4 is a rear face-view of the same. Fig. 5 is a transverse vertical section of the bag-frame fastener, said section being taken on line 5—5 in said Fig. 3, and said view being made on an enlarged scale; and Fig. 6 is a similar sectional representation of the same, but showing the knob or fingerpiece in its manually manipulated relation to the shell or box of the fastener. Fig. 7 is a bottom view of the bag-frame fastener, said view being made on the same scale, as the parts illustrated in said Figs. 1 to 4 inclusive.

Similar characters of reference are employed in all of the above described views, to indicate corresponding parts.

Referring now to the said drawings, the reference-characters 1 and 2 indicate portions of the usual bag-frame-sections, upon one of which, as 1, is secured by means of fastening lugs, as 4, or by other suitable fastening means, a suitably formed shell or box. This shell or box, which is of elongated configuration, comprises a top or upper face-plate 3, a front face 5, a rear face 6, and the

ends 7, from the lower marginal edges of which extend the said fastening lugs 4. The central portion of the front face 5 is preferably bowed, as at 8, and is provided with a 5 hasp-plate receiving-opening, as 9; and, in like manner, the rear face 6 is also preferably bowed, as at 10. With slight changes in the width of the shell or box thus provided, it will be clearly evident that the 10 said bowed portions 8 and 10 may be entirely omitted, if desired. The upper face-plate 3 is also provided with suitably formed openings, as 11 and 12, and the vertically extending elongated opening, as 13, the purposes of said openings 11, 12 and 13, being self-evident from an inspection more particularly of Figs. 5 and 6 of the drawing, and being presently more fully stated. Normally, resting upon the outer surface of the 15 said upper face-plate 3, so as to close the said openings 11 and 12, is the flat surface 15 of an ornamental knob or fingerpiece, as 14, which may be of any suitable configuration. Extending from said flat surface 15, into 20 and through the opening 12, is a suitably formed post, as 16, which is provided with a rearwardly projecting pin or stud 17 extending normally into the herein-above mentioned elongated opening or slot 13. Across 25 its front face, the said post 16 is made near its lower end with a laterally extending slot or cut-away portion, as 18, in which is placed and held the centrally bowed portion of a suitably curved spring-member 19. The free 30 end-portions of said spring-member extend upwardly in opposite directions, the preferably curved ends 20 of the said spring-member being in friction retaining engagement with the corner-portions 21 of the shell or 35 box, at the junction of the upper face-plate 3, the rear face 6, and each end 7, as will be clearly understood from an inspection of Figs. 5, 6 and 7 of the drawings. Extending from the said flat surface 15, normally 40 into the opening 11 in the upper face-plate 3 and into the opening 9 of the front face 5 of the shell or box, is a hasp-engaging post or stud 22, said post or stud being provided upon its lower front portion with an inclined or rearwardly tapering end 23, adapted 45 to be engaged by the usual hasp 25 which extends rearwardly and at right angles from a hasp-plate, as 24, suitably secured by means of rivets 26, or other fastening means, 50 to the frame-section 2. Normally, the spring-member 19 retains the knob or fingerpiece 14 and the posts 16 and 22 in the positions, indicated in said Fig. 5 of the drawings, and when the frame-section 2 is closed 55 within the frame-section 1, the hasp 25 engages the tapering end 23 of the post or stud 22, so as to sufficiently raise the parts and allow the post or stud 22 to spring into 60 its retaining engagement with an opening or perforation, as 27, with which the hasp 25 is

provided. To disengage the said post or stud 22 from its holding or retaining engagement with the hasp 25, to bring the hinged frame-sections 1 and 2 into their separated or open relation, a slight lifting pressure upon the part 28 of the knob or fingerpiece 14 will bring the latter into its raised position represented in Fig. 6 of the drawings, so that the two frame-sections can be opened, as will be clearly evident. 75

The purpose of the previously mentioned pin or stud 17 which, normally, extends into the elongated opening or slot 13 is to prevent any pivotal movement of the knob or fingerpiece 14, by its engagement with the edge portion 29 at the top of the opening or slot 13, should pressure inadvertently be applied upon the part 30 of the knob or fingerpiece, as will be clearly understood from an inspection of Figs. 5 and 7 of the drawings. 80 After the knob or fingerpiece 14 has been raised, and upon the removal of further pressure from the part 28 of the knob or fingerpiece, the distorted spring-member or torsion spring 19, in assuming its normal position, will return the raised knob or fingerpiece and its posts 16 and 22, from the position indicated in Fig. 6 of the drawings to their normally lowered position represented in Fig. 5 of the drawings. 85

Of course I am aware that some changes may be made in the general arrangements and combinations of the several devices and parts, as well as in the details of the construction of the latter, without departing 100 from the scope of the present invention as set forth in the foregoing specification, and as defined in the clauses of the claim which is appended to the said specification. Hence, I do not limit my present invention to the 105 exact arrangement and combinations of the various devices and parts, as described in the said specification, nor do I confine myself to the exact details of the construction of the said parts, as illustrated in the accompanying drawings. 110

I claim:—

1. A bag-frame fastener comprising a shell or box formed in its upper face with openings, and in its front face being formed with an opening, a fingerpiece loosely mounted upon said upper face and over the openings in said upper face, a spring-engaging post extending from said fingerpiece into and through one of the openings in the upper face, a spring within said shell or box having a portion in engagement with said post, and a hasp-receiving stud extending from said fingerpiece into the other opening in said upper face and into the opening in the front face of the shell or box, substantially as and for the purposes set forth. 120

2. A bag-frame fastener comprising a shell or box formed in its upper face with 125

openings, and in its front face being formed with an opening, a fingerpiece loosely mounted upon said upper face and over the openings in said upper face, a spring-engaging post extending from said fingerpiece into and through one of the openings in the upper face, a spring within said shell or box having a portion in engagement with said post, a hasp-receiving stud extending from 5 said fingerpiece into the other opening in said upper face and into the opening in the front face of the shell or box, and means connected with said spring-engaging post adapted to be brought into arrested engagement with a portion of said shell or box to prevent movement of the fingerpiece in a 10 forward direction.

3. A bag-frame fastener comprising a shell or box formed in its upper face with 20 openings, and in its front face and in its rear face with other openings, a fingerpiece loosely mounted upon said upper face and over the openings in said upper face, a spring-engaging post extending from said 25 fingerpiece into and through one of the openings in the upper face, a spring within said shell or box having a portion in engagement with said post, a hasp-receiving stud extending from said fingerpiece into the other opening in said upper face and into the opening in the front face of the shell or box, and a stop-pin extending rearwardly from 30 said spring-engaging post, said pin projecting into the opening of the rear face of said shell or box and being adapted to be brought into arresting engagement with a marginal portion of said rear face surrounding 35 said opening to prevent movement of the fingerpiece in a forward direction, substantially as and for the purposes set forth.

4. A bag-frame fastener comprising a shell or box formed in its upper face with an opening, a fingerpiece loosely mounted upon said upper face, a spring-engaging 45 post extending from said fingerpiece into and through the opening in the upper face, said post being provided near its lower end with a laterally extending slot, a bowed torsional spring having its central portion ar- 50 ranged in said slot, and the end-portions of said spring extending in upward directions of said shell or box and resting in frictional engagement with the inner and upper corner-portions of said shell or box, and a hasp- 55 receiving stud extending from said fingerpiece, substantially as and for the purposes set forth.

5. A bag-frame fastener comprising a shell or box formed in its upper face with an opening, a fingerpiece loosely mounted upon 60 said upper face, a spring-engaging post extending from said fingerpiece into and through the opening in the upper face, said post being provided near its lower end with a laterally extending slot, a bowed portion 65 arranged in said slot, and the end-portions of said spring extending in upward directions within the shell or box and resting in frictional engagement with the inner and upper corner-portions of said shell or box, 70 and a hasp-receiving stud extending from said fingerpiece, and means connected with said spring-engaging post adapted to be brought into arrested engagement with a portion of said shell or box to prevent move- 75 ment of the fingerpiece in a forward direction.

6. A bag-frame fastener comprising a shell or box formed in its upper face with 80 openings, and in its front face and in its rear face with other openings, a fingerpiece loosely mounted upon said upper face and over the openings in said upper face, a spring-engaging post extending from said 85 fingerpiece into and through one of the openings in the upper face, said post being provided near its lower end with a laterally extending slot, a bowed torsional spring having its central portions arranged in said slot, and the end-portions of said spring 90 extending in upward directions within the shell or box and resting in frictional engagement with the inner and upper corner-portions of said shell or box, a hasp-receiving stud extending from said fingerpiece 95 into the opening in the front face of the shell or box, and a stop-pin extending rearwardly from said spring-engaging post, said pin projecting into the opening of the rear face of said shell or box and being adapted 100 to be brought into arresting engagement with a marginal portion of said rear face surrounding said opening to prevent movement of the fingerpiece in a forward direction, substantially as and for the purposes 105 set forth.

In testimony that I claim the invention set forth above I have hereunto set my hand this 18th day of August, 1914.

BENNO VOM EIGEN.
